VESSEL FOR TRANSPORTING AND
DROPPING DEPTH BOMBSSydney B. Leonardi, Jr., New Rochelle, N. Y., as
signor of one-half to Harold H. Pelzer and
William Pelzer, both of New York, N. Y.

Application September 17, 1938, Serial No. 230,403

8 Claims. (Cl. 114—20)

This invention relates to the means employed for transporting and dropping depth bombs into the sea, harbors and rivers, and primarily to depth bombs which are caused to explode 5 through the operation of devices actuated by the water pressure at predetermined depths. Heretofore it has been the practice to carry such bombs in ships or floating vessels to the point where it is desired to drop the bomb overboard. 10 This procedure obviously subjects the transporting vessel and operators to danger, and the main object of the present invention is to provide a mobile carrier capable of being projected or driven by power within the carrier to a given 15 point under or upon the surface of the water and which carrier will contain one or more depth bombs and means for automatically releasing the bombs for dropping into the water, and which carrier will float after release of the bombs and be recoverable for further use.

In carrying the invention into effect I preferably employ a vessel of the automobile torpedo type so that the bomb carrying vessel may be launched through the usual torpedo launching tubes, and when the bomb carrier is provided with a power plant for propelling the carrier and automatic steering and depth regulating means, I prefer to employ the apparatus with which automobile torpedoes are usually provided. The power plant and controlling mechanism for propelling and directing the bomb carrier are contained within a closed chamber at the tail end of the vessel. Forward of this chamber is a compressed air chamber, and immediately in advance of this chamber the vessel is divided into three compartments, one being an upper air chamber for buoyancy and two separate lower chambers adapted to contain the depth bombs. The bomb chambers are closed by hinged wall sections having locking bolts, and which sections are preferably double walled to provide additional air chambers, and adjacent each bomb chamber is housed mechanism for unlocking the hinged sections to release the bombs. The bow 40 end of the vessel is closed to form a further air chamber for buoyancy, and this chamber may be weighted below the axial center of the vessel to provide fore and aft balance and to maintain the vessel on an even keel. The bomb releasing mechanism is actuated through a reducing gear connected with the air turbine or propeller shaft and the functioning of the releasing mechanism is controlled by timing disks and range setting dials whereby the bombs will 45 be released at predetermined distances from the

point of launching of the carrier and the carrier propelling and directing mechanism shut down to permit the carrier to rise and float on the surface to be recovered subsequently by the vessel from which it was launched or by other 5 vessels.

The invention is illustrated in the accompanying drawings, in which,

Figure 1 is a longitudinal elevation of a vessel of the automobile torpedo type provided with 10 bomb chambers.

Figure 2 a vertical longitudinal section of the forward half of the vessel shown in Figure 1.

Figure 3 a similar view of the rear half of the vessel.

Figure 4 an enlarged cross-sectional view on the lines 4—4 of Figure 2.

Figure 5 an enlarged vertical longitudinal section taken between the lines 5—5 of Figure 2.

Figure 6 an enlarged cross-sectional view on the lines 6—6 of Figure 2, and

Figure 7 an enlarged plan view of the range setting dial.

Referring to the drawings, and more particularly to Figure 1, 2 and 3, A indicates a vessel 25 of the automobile torpedo type having propellers 1, steering rudders 2, depth controlling rudders 3, stern chamber 4 in which is housed the usual propelling and controlling apparatus comprising an air turbine 5 for driving the propellers, turbo-electric generator 6, air heater 7 for heating the air supplied to the turbines, a gyroscope 8 for controlling the steering rudders, and a device 9 for controlling the depth 30 rudders. These pieces of apparatus and the operating connections are not fully illustrated or described in detail since they form no part of the present invention and are well known and may be of any of the well known types.

The cylindrical shell A is divided into compartments by three bulkheads a, b and c to provide air and watertight chambers. Bulkheads a and b form with the shell A the compressed air chamber 10 from which air pipes 11 extend to the heater 7 and from which the heated air is conducted 40 to the propeller turbine 5 and to the turbo-generator 6 controlled by trigger 12. Bulkhead c with shell A forms the bow air chamber 13 in which is fixed below the axial center of the vessel a balancing weight 14. Between the bulkheads b and c 45 the shell A is divided into bomb chambers 15 and 16 having semi-circular openings or ports closed by semi-circular lids 17 hinged at the forward ends by hinges 18. These chambers are formed by semi-cylindrical inner shell sections 19, shown 50

in cross-section in Figure 6, having longitudinal flanges 20 which are seam-welded to the outer shell along the edge of the semi-circular opening. The forward ends of these inner shell sections are closed by semi-circular flanged disks 21 having horizontal flanges 22 as seen in Figures 2 and 5. These flanges 22 extend across the full diameter of shell A, the disk at chamber 16 being welded air and watertight to bulkhead c and the disk 21 at chamber 15 being similarly welded to a semi-circular disk 23 having a flange 24. A similar disk 23 having a flange 24 extends across the shell A at the rear of chamber 15 and this disk has a horizontal plate 25 welded at the angle and to the bulkhead b as seen in Figure 2. The rear ends of the inner shell sections 19 are curved as seen in Figure 2 and are closed by curved semi-circular disks 26 which extend close to the bottom of shell A, and these disks are welded to the flanges 24 of disks 23. Thus the partitions formed by shell sections 19, disks 21, disks 26, flanges 22 and 24 and plate 25, form with the outer shell A and bulkheads b and c, an air and watertight chamber 27. To strengthen the section of shell A at the bomb chambers a series of arched plate ribs 28 are rigidly secured between the shell sections 19 and shell A extending entirely around the sections 19 from flanges 20. The hinged lids 17 have an inner wall 17^a spaced therefrom by lateral flanges 17^b and peripheral flanges 17^c and 17^d which are welded to the outer shell sections 17, as seen in Figures 5 and 6, thereby making air and watertight chambers of the hinged lids. Each lid 17 is provided with a sliding spring actuated bolt 29 the nose of which is bevelled to slide over the edge of shell A and engage the inner side thereof to lock the lid.

The dimensions and shape of the bomb chambers may be varied to suit the dimensions and shape of the bombs to be carried therein. For illustration the bombs 30 and 31 are shown as cylindrical in shape and the length of the chambers between plates 21 and 26 will be such as to hold the bombs against longitudinal movement when enclosed in the chambers. The diameter of the bomb chamber will be greater than the diameter of the bomb and to hold the bomb against lateral movement the inner wall 17^a of the lid section is provided with longitudinal ribs 17^e and rubber pads 19^a secured to the inner side of shells 19 and which pads will be compressed slightly by the pressure of the bomb when the lid is closed. When the lid is unlocked the weight of the bomb will swing the lid downward as indicated in broken lines in Figure 1, the ribs 17^e serving as skids on which the bomb will slide off the lid section. At the lower edge of plates 26 a recess is provided for a rubber cushion 32, Figure 5, against which the projection 33 on the lid section strikes when locking the lid. The lateral flanges 17^b and the end peripheral flanges 17^f, Figure 6, of the inner wall of the lid 17 are grooved as indicated to receive rubber strips 17^g to serve as packing to reduce the seepage of water into the bomb chamber. Seepage of water into the bomb chamber during the short period the carrier travels through the water before the bomb is released will have no effect on the bomb while in the chamber since the pressure would be insufficient to operate the firing mechanism of the bomb.

The releasing mechanism for releasing the bombs comprises a crank-lever 34 for disengaging the bolt 29 pivoted on bracket 35 which is secured on plate 28, a link 36, cam-rod 37, and cam 38 on the front face of timing disk 39 having

a hub 40 sleeved on shaft 41 journalled in bearings 42. The base 43 of the bearing 42 is bored to form a sliding bearing for cam-rod 37 and counter-bored to receive a packing and gland 44. A coiled spring 45 on the rod 37 exerts downward pressure on the rod to normally hold the crank-lever out of engagement with the nose of bolt 29. Timing disk 39 is loose on shaft 41 and on the rear face has an enlarged hub 46 on which mitre gear teeth 47 are cut, and the interior diameter 10 of this hub is bored to form the driven element of a roller clutch of any suitable type, the driving element of which is illustrated as a hub 48 keyed to shaft 41 and carrying rollers 49 working within hub 46 to engage said hub for rotation in one direction and permitting the hub 46 and timing disk 39 to be freely rotated in the opposite direction independently of shaft 41. Permanently in mesh with mitre gear 47 is a mitre gear 50 keyed to stub-shaft 51 journalled in bearing 52 bolted to a recessed seat 53 formed in the hand-hole cover plate 54 which is seated flush with, sealed and bolted to the shell A as seen in Figure 5. In the recessed seat 53 is seated a range setting dial 55 keyed and bolted to the stub-shaft 51, and the bearing for shaft 51 is counter-bored to receive a packing and gland 56. Dial 55 is graduated to indicate distance, for instance, in yards, each graduation as illustrated in Figure 7 representing twenty yards, and the disk constituting the dial is made sufficiently large and thick to provide for spanner wrench holes 57 whereby the dial may be rotated to rotate shaft 51, gears 50 and 47 and timing disk 39 to set cam 38 for effecting the operation of cam-rod 37 and crank-lever 34 to shift the locking bolt 29 for releasing a bomb at a predetermined distance of travel of the carrier vessel from the moment of launching and operation of the control trigger 12.

Release mechanism shaft 41 is driven at a greatly reduced speed through a chain drive 58 and reducing gear 59 of any suitable type mounted on or adjacent to and driven by air turbine 5, see Figure 3. Shaft 41 is illustrated as in one length but it will be understood the shaft 41 may be in several sections joined by couplings, and passages through a tube 60 extending between bulkheads a and b. When the carrier vessel is launched and trigger 12 is tripped to start the propelling and other apparatus operating, shaft 41 also begins rotation and through the roller clutches rotates the timing disks of the bomb releasing mechanisms. The timing disks may be set by the range setting dials to release the two bombs simultaneously, for instance, at a point one thousand yards from the point of launching, by turning the dials individually to the graduations indicating that distance. The rotation of the dials in effecting these settings rotate the timing disks individually backward to set the cams 38 at a position where, when the shaft 41 begins to rotate, the disks through the engagement of the roller clutches rotate at the same speed as the shaft to eventually cause the cams to engage and raise the cam-rods to release the bombs. When it is desired to release the bombs at spaced intervals, for instance, twenty yards apart, the forward setting dial which controls the release of bomb 31 from the forward chamber will be set one graduation further than the dial which controls the release of bomb 30, so that the bomb 30 which will be released first is dropped twenty yards in advance of the dropping of bomb 31.

On the rear face of the forward timing disk 39, 75

that is the one controlling the release of the second bomb, a cam 61, Figure 4, is adjustably set with respect to the release operating cam 38 a definite number of degrees peripherally behind the cam 38. This cam 61 is positioned to engage a pair of electric circuit contacts 62 mounted upon the base 43 in alignment with the cam-rod 37 so that after the second or last bomb is released the cam 61 closes the circuit through cable 10 63 to a solenoid 64, Figure 3, which is energized from generator 6. The location of cam 61 on the timing disk relative to releasing cam 38 will be determined by the distance it is desired the vessel shall travel after releasing the last bomb. 15 Solenoid 64 is mechanically connected to trigger 12 and when energized pulls the trigger back to its initial or starting position, cutting off the air supply to the propeller turbine and turbo-generator, thereby permitting the carrier to slow 20 down and come to rest, and whereupon the depth control device becomes ineffective and the discharged carrier rises to the surface with the bow end raised owing to the discharge of the load from the forward end. To facilitate the towing 25 of the carrier vessel back to the launching ship or station a ring 65 is provided at the bow for engagement by a boat-hook or towing line. After the carrier vessel is placed aboard the launching ship or station it may be reloaded with bombs 30 and the compressed air tank recharged for further use, and the range setting dials are reset to zero preparatory to setting them and the timing disks for the next discharge.

What I claim is:

35 1. In a vessel of the character described, the combination of an overall shell, a bomb chamber therein of smaller cross-sectional area than said shell and having its longitudinal center below the longitudinal center of said shell, an air chamber surrounding approximately the upper half of said bomb chamber, a releasable shell section at the bomb chamber for retaining a bomb therein, a locking device for said releasable section, a mechanism for actuating said locking device to release said shell section, and means for adjusting said mechanism to release said shell section at a predetermined interval.

2. In a vessel of the character described, the combination of an overall shell, a plurality of 50 bomb chambers separately enclosed within said shell and in axial alignment therein, a releasable shell section at each bomb chamber for retaining a bomb therein, a locking device for each releasable shell section, a mechanism for actuating each locking device to release said shell sections independently of each other, an adjustable actuating means for each of said mechanisms, and

a common drive shaft for said actuating means.

3. In a vessel of the character described, the combination of an overall shell, bulkheads and partitions therein forming separate bomb chambers in axial alignment, said chambers being of 5 smaller cross-sectional area than said shell and having their longitudinal centers below the longitudinal center of said shell, an air chamber surrounding approximately the upper half of each bomb chamber, a releasable shell section at each 10 bomb chamber for retaining a bomb therein, a locking device for each releasable section, a mechanism for actuating each locking device to release said shell sections independently of each other, an adjustable actuating means for each of 15 said mechanisms, and a common drive shaft for said actuating means.

4. In a vessel as defined in claim 1, a rotary timing disk having a cam for actuating the releasing mechanism, and a setting dial operatively connected with the timing disk for setting same to actuate said mechanism at a predetermined interval.

5. In a vessel as defined in claim 1, a rotary timing disk having a cam for actuating the releasing mechanism, a motor driven shaft and one-way clutch thereon for rotating said disk in one direction, and a setting dial geared to said disk for rotating same in the opposite direction for setting said disk to actuate said mechanism 30 at a predetermined interval.

6. In a vessel as defined in claim 1, a rotary timing disk having a cam for actuating the releasing mechanism, a setting dial operatively connected with the timing disk for setting same 35 to actuate said mechanism at a predetermined interval, and a means actuated through the timing disk for discontinuing rotation of the disk after release of a bomb from the bomb chamber.

7. In a vessel as defined in claim 1, a rotary motor driven timing disk having a cam for actuating the releasing mechanism, a setting dial operatively connected with the timing disk for setting same 40 to actuate said mechanism at a predetermined interval, and a means actuated through the timing disk for shutting off the power to the motor after release of a bomb from the bomb chamber.

8. In a vessel as defined in claim 2, a plurality of rotary timing disks each having a cam 50 for actuating a releasing mechanism and driven by a common driving shaft, and a setting dial for each timing disk for setting same to actuate said mechanisms to release the shell sections simultaneously or independently of each other at predetermined intervals.

SYDNEY B. LEONARDI, JR.
